UNITED STATES PATENT OFFICE.

CHARLES HERRMANN, OF BROOKLYN, NEW YORK, ASSIGNOR TO CHAS. CORY & SON,
INCORPORATED, OF NEW YORK, N. Y., A CORPORATION OF NEW YORK.

ANNUNCIATOR DROP.

Application filed February 16, 1921. Serial No. 445,385.

To all whom it may concern:

Be it known that I, CHARLES HERRMANN, a citizen of the United States, and resident of Brooklyn, in the county of Kings and 5 State of New York, have invented certain new and useful Improvements in Annunciator Drops, of which the following is a specification.

My invention relates to a signalling apparatus and more particularly to an annunciator drop signalling means and has special reference to the provision of an annunciator drop of a self restoring type in which the parts are so constructed and arranged as to 10 reduce vibration of the movable parts when in active and inactive positions.

One of the principal objects of my present invention comprehends the provision of a drop of the type referred to in which the 15 movable parts, such as the shutter element and the armature shall be self restoring, the parts being so constructed and related as to be positive in action in both its moving and stationary phases. To utilize the gravity 20 of the movable parts to effect the self restoring function permits the utilization of simple elements and the simple arrangement which is highly desirable in apparatus of 25 this type, where compactness and especially smallness of space between centers of drops 30 is the prime desideratum. It has been found, however, that in apparatus of this type where gravity is dependent upon for the moving and the positioning of elements, 35 and especially where such apparatus is used in series with an audible signalling means such as a bell or buzzer providing an intermittent current, that there is a great 40 tendency of parts to move from their pre-determined positions, especially when such drops are mounted on conveyances such as elevators, ships, etc., and especially when the drops are operated while the conveyances 45 are in transit. The movement, vibration or shock which the drop is subjected to when thus operated, especially with an intermittent current which in itself causes chattering, 50 is transmitted to the movable parts thereof, with the result that the shutter is uncertain in action and vibrates while in either its active or inactive position, result-

ing not only in a disagreeable chatter of the instrument but also in a blurred visual signal element resulting from the vibrations thereof. One of the principal objects of my present invention, therefore, is to provide a gravity reset annunciator drop having the desired simplicity of parts and arrangement and small compass, in which the gravity actuated elements will be positive 55 in action and in which vibration of parts will be reduced to a minimum.

Viewed from another aspect, my invention comprehends the provision of a movable signalling element having a gravitationally assumed inactive position, the element being movable to an active position by electromagnetic means, the said element being securely held in its gravitated position preferably by a gravity moment and in 60 its active position by a magnetic moment for the purpose of minimizing the vibrations thereof.

Another object of my invention includes the provision of an annunciator drop of the type referred to in which the parts are so related as to combine a decreased reluctance of the magnetic paths with consequent increase in the flux density, with movable magnetic elements so associated with 65 the stationary magnetic elements providing the magnetic paths as to have a facility of movement with respect thereto, means being provided to prevent or minimize the magnetic adhesion between the movable and stationary magnetic elements. Where a gravity moment active on the drop resists a magnetic moment operative thereon, which is generally the case in gravity reset apparatus, the reluctance of the magnetic paths should 70 be small to increase the attracting power of the magnet, it being highly desirable to reduce magnetic friction, that is to say friction between movable and stationary magnetic or magnetized elements in order to 75 decrease the resulting resistance to such magnetic attraction. My invention comprehends the provision of a drop in which the magnetic adhesion between the parts is 80 minimized, reducing magnetic friction to a 85 minimum.

Still further objects of my invention in-

clude the provision of a gravity reset signalling apparatus in which the movable parts may be securely locked in position and more particularly in both its active and inactive positions; the further provision of an apparatus of this type in which a unitary locking means is provided for holding the movable parts in both the active and inactive positions; the provision of a novel solenoid 10 system for operating the movable parts and the locking means and the general provision of apparatus of this nature in which the parts are capable of simplicity of manufacturing operation, facility of assembly, 15 compactness of arrangement and surety of action.

To the accomplishment of the foregoing and such other objects as may hereinafter appear, my invention consists in the elements 20 and their relation one to the other, as hereinafter particularly described and sought to be defined in the claims, reference being had to the accompanying drawings which show preferred embodiments of my invention and 25 in which—

Figure 1 is an elevational view of one form of my annunciator drop with parts shown in section and showing the active position of the annunciator in dotted line 30 position; inactive position being shown in full lines,

Figure 2 is a plan view of the same,

Figure 3 is a view of a modification of my annunciator drop with parts shown in 35 section and showing my novel locking means therefor,

Figure 4 is an elevational view of the same with parts broken away and showing the signal element in active position.

Referring to Figures 1 and 2 of the drawings, the annunciator drop includes the electromagnet 10 stationarily mounted, as on a board or plate 11, it being understood that a plurality of such electromagnets are 40 mounted in adjacent positions on such board or plate 11. The magnet is provided with the usual core 12 forming its pole piece, the magnet being secured on plate 13 formed preferably of magnetic material, such as 45 iron, the magnet being secured to said plate as by means of a nut or bolt 14 received by the core 12 of the magnet. The magnet and plate are held in secured position on the board 11, preferably by such securing means 50 as bolts 15, shown, for example, in Figure 1 of the drawings. The plate 13 is preferably formed integrally with a bracket 16, the said bracket being supplied with an upturned 55 supporting portion 17 for supporting the movable parts of the drop, to be described presently. It will be noted that the bracket 60 16, plate 13 and support 17 are magnetically connected to the magnet core 12 at one end of said core, the support 17 being spaced 65 from the other end of the core to provide

an air gap in which the movable armature to be presently described is adapted to move, the bracket, plate and support being in effect an extension of the core providing thus a 70 magnetic path for the lines of flux when the magnet 10 is energized, these parts being preferably thickened, as shown in the drawings, to provide a path of relatively decreased reluctance.

On the support 17 is preferably oscillatably mounted the armature 18, having a leg portion 19 adapted to be received in a recess 20, formed preferably centrally and at an end of the support 17, the armature 18 being pivotally mounted on the support 17, 80 a pin 21 received by aligned bores in the support 17 and leg 19 forming the pivotal mounting for the said armature 18. For the purpose of reducing or minimizing magnetic adhesion or magnetic friction between 85 the movable armature 18 and the stationary magnetic support 17, the pin 21 is preferably made of a nonmagnetic material, opposed washers 22 also formed of nonmagnetic material being inserted between the movable armature 18 and the walls adjoining the recess 20.

For the purpose of providing a device in which the armature and the parts movable therewith will be steadily maintained in active position when the magnet is energized, I arrange the parts in such manner that when in active position a magnetic moment will be operative on the armature to forcibly hold the parts in such active position. To this end the armature 18 comprises preferably a wing element or a foot element having a heel portion 23 and a toe portion 24, the said armature being attracted by the core 12 when the magnet is energized 105 and moved into active position, as shown in dotted lines in Figure 1 of the drawings, the toe portion 24 when moved to active position being so arranged as to be stopped by a portion of the support 17, as clearly shown in 110 Figure 1 of the drawings. The parts are so constructed that in the position shown in dotted lines in the said Figure 1 the center of magnetic attraction is beyond or above the pivotal support 21, as viewed in 115 Figure 1. With the parts so arranged and during energization of the magnet 10, a magnetic moment active on the armature 18 will be exerted, tending to move the armature in clockwise direction, as viewed in 120 Figure 1, this magnetic moment forcing the toe 24 of the armature in close contact with the support 17, this activity holding the armature steadily in its active position and resisting and minimizing vibration 125 of the armature while in such active position. I may obtain this magnetic moment in any of several ways as, for example, by so proportioning the heel and toe portions of the armature as to situate the greater mass 130

of magnetic material above the horizontal plane passing through the pivotal axis 21, thus securing a center of magnet attraction above the said pivotal axis. To attain the 5 same end I may also so contour the foot portion as to provide a flat heel 25 and an eccentric or cam toe 26, a part of the flat heel and a part of the eccentric toe being positioned opposite the core 12 when the armature is 10 in active position. With this construction it will be seen that the air gap between the magnet core 12 and the armature 18 is in effect wedge shaped, being wider at the bottom than at the top, the effect of this 15 arrangement being that when the armature is in active position as shown in dotted lines in Figure 1, the magnet core 12 cooperates with the armature 18 with a tendency to further reduce the air gap therebetween, the 20 resulting effect obtained being a continued pull on the armature 18 about its axis of oscillation with a magnetic moment produced about such axis. As an alternative I may arrange the axis of the core 12 above 25 the horizontal plane passing through the pivotal axis 21 so that when the parts are in magnetic equilibrium the center of magnetic attraction is at the point desired to provide the magnetic moment referred to. This latter arrangement, for example, is 30 more clearly illustrated in the form shown in Figure 3 of the drawings.

For the purpose of minimizing magnetic adhesion between the armature and its support when the armature is in its active position I preferably construct the armature element 18 of laminated parts, there being provided opposed laminæ 27 made of magnetic material and an interposed lamina 28, 40 preferably made of a nonmagnetic material such as brass, these parts being preferably secured together, as by means of a riveted bolt 29. The nonmagnetic lamina 28 is so contoured as to provide a portion protruding from the toe and heel surfaces of the laminæ 27, the toe end of lamina 28 being adapted to contact with the support 17, the toe portions of the opposed magnetic laminæ 27 being in this manner held out of contact 45 with the magnetic support 17. By this means the sticking between magnetic elements or the magnetic adhesion between the parts is minimized, permitting a quick return of the armature to inactive position 50 when the magnet 10 is deenergized.

The signaling element proper, designated as 30, comprises a shutter including the usual plate 31 having the desired imprint of legendary matter thereon, the signalling element 60 having yoke arms 32 preferably journaled on the pivot pin 21 and held thereon by enlarged heads of the said pivot pin, the yoke arms 32 terminating in parallelly arranged portions 33 attached to the laminæ 65 comprising the armature 18, the rivet 29

being utilized for attaching the parallel portions 33 to the said armature 18. In this manner the signalling element is preferably directly attached to the armature and is movable therewith in a simple manner. 70

The armature and the signalling element connected thereto are adapted to be self restoring, gravity of the parts being preferably utilized to accomplish the self restoring function. To this end the parts are 75 so arranged that the center of gravity of the movable elements comprising the armature and the signalling element is located to the left of pivot 21, as viewed in Figure 1 of the drawings, when the movable elements 80 are in their active position, as shown in dotted lines in the said Figure 1. As will be apparent, when the magnet 10 is deenergized, the gravity of the parts will move the signalling element to its inactive or inoperative position and into position as shown in full lines in the said Figure 1. For the purpose of holding the movable elements in their inactive position a projection 34 preferably stamped out or struck up from one 85 of the yoke arms 32 is provided, the projection being adapted to engage the support 17, as shown for example, in Figure 1 of the drawings. In order to hold the armature and the signalling element in inactive position 90 against vibration of the parts, a gravity moment is preferably provided, the parts being so arranged that the center of gravity of the movable elements, as viewed in Figure 1, is to the left of the pivot 21 when the parts are in inactive position, as shown in full lines in the said figure, this resulting in the production of a gravity moment 95 tending to move the armature and its supported parts counterclockwise with the projection 34 urged or forcibly held against the support 17. 100

Referring to the form of my device shown in Figures 3 and 4 of the drawings, in addition to the parts already described, I may 110 also provide, as shown in the said Figures 3 and 4, a locking means to hold the movable parts in either its active or inactive position or both, my preferred arrangement comprehending a unitary locking means for 115 holding the movable parts in both of its positions. This modified form of my apparatus includes the stationary magnet 10' having the core 12', these parts being mounted on the bracket 16', the core being secured to the said bracket by means of the securing element 14', the bracket, in turn, being 120 stationarily mounted on the board 11' as by means of the securing elements 15', similar to the form shown in Figures 1 and 2 of the drawings. The movable parts of my device here, as in the form shown in Figures 1 and 2 of the drawings, comprise the armature 18' pivotally mounted on the support 17', as by means of the pivot 21', the signal- 125 130

ling element 30' having the legendary plate 31', being directly connected preferably to the armature 18', the projection 34' being also provided for the purpose of coacting 5 with the support 17' to provide the stopping means for the movable elements when in inactive position.

In the modified form of my device the magnet core is divided into two sections 10 12' and 12'', a coupling 12''' being provided connecting the two core portions, the said coupling being made of a nonmagnetic material such as brass, for example. The cores 12' and 12'' are alined, as shown in 15 the drawings, the said cores being provided with a central bore 35 in which is movably mounted a plunger made, for example, of iron, as 36, the said plunger being provided with a reduced end portion 37 movable in 20 a reduced bore 38 provided in the said core 12', the said plunger being adapted to cooperate with the armature to lock the same in active and inactive position, the end portion 37 cooperating with the toe of the armature to force the same in its inactive position and cooperating with a notch 39 provided in the said armature to lock the same in active position, as shown for example, in 25 Figure 4 of the drawings. The plunger 36 is preferably spring pressed, a spring 40 housed in the core 12'' being provided for normally urging the plunger with its end portion 37 in the path of armature movement and against the toe of the armature 30 as shown in Figure 3 of the drawings.

For the purpose of unlocking the armature to permit the same to move to active position, I provide means for moving the plunger 36 inwardly in its housing in the core, such means comprising solenoid winding 41 connected in series with the magnet winding 10', as by means of lead 44, the magnet and the solenoid winding being thus connected in series and with an audible signalling element 44^a and across the line wires 45 and 46, the usual switch 47 being provided in such circuit. As will be apparent, upon closing the switch 47 both the magnet 10' and the solenoid 41 will be energized, 45 the solenoid 41 being active on the plunger 36 to move the same inwardly and to unlock the armature 18', the magnet 10' being active to move the armature 18' to active position with the toe portion of the armature stopped by the support 17'. Upon release of the actuating switch 47 the magnet 10 and solenoid 41 will be deenergized and as will be apparent, the spring 40 will urge 50 the plunger 36 outwardly, the end portion 37 moving in the notch 39 and holding the armature and signal element locked in active position.

For the purpose of releasing the lock described above to permit gravitational movement of the armature to inactive position, I

preferably provide a second solenoid winding 42 arranged concentrically with the winding 41, to be active on the plunger 36, the said second solenoid 42 being connected in an independent circuit and across the lines 48 and 49, switch 50 being provided, as usual, in the second circuit. Upon closing the switch 50 it will be obvious that the solenoid winding 42 will be energized, the 70 excitation of this solenoid moving the plunger 36 inwardly against spring action, 75 unlocking the armature and permitting its gravitated movement.

For the purpose of reducing magnetic adhesion between the armature and the locking element 37 in contact therewith, the notch 39 formed in the central lamina 28' has a bottom wall situated above the bottom walls of the notches formed in the magnetic laminae 27', as shown for example in 80 Figure 3 of the drawings. With this construction it will be evident that the magnetic plunger 36 will not contact with the magnetic portions of the armature 18', reducing magnetic adhesion between the parts. For the purpose of supplying an additional support for the extended solenoid system and for the further purpose of reducing the reluctance of the magnetic path passing 85 through the core 12', I provide the plate 90 43, for magnetic connection between the core 12' and the bracket 16.

The operation and use of my annunciator drop signalling system will, in the main, be apparent from the above detailed description of structure and operation. It will be obvious that I have provided an annunciator drop of the self restoring type and more specifically of the gravity reset type, in 100 which the parts are arranged in a simple manner and in which the parts are adapted for certainty of operation, magnetic adhesion and friction being minimized, in which the movable elements are held in predetermined positions in such manner as to reduce liability of rebounding movement or vibration thereof, a novel and simple locking means and its operative solenoid system being provided for efficiently locking the movable parts in the desired predetermined 105 positions.

While I have shown and described my device in the preferred form, it will be obvious that many changes and modifications may be made in the structure disclosed without departing from the spirit of the invention, defined in the following claims.

I claim:

1. In a signalling apparatus, an electromagnet with its pole piece, a laminated armature including magnetic and non-magnetic laminae portions mounted so as to be movable transversely with respect to the pole of the magnet, a signal element connected to the armature for movement therewith the 125 130

pole piece having an extension providing a magnetic path for the lines of flux and a stop means for limiting the motion of the armature in one direction, the nonmagnetic portions extending to engage the stop means, said magnet pole piece and armature including means whereby the magnetic pull of the energized magnet on the movable armature will move the armature to the said 10 limiting position and exert a continued pull on the armature in the said position to force the non-magnetic portion of the same into engagement with the stop means to prevent vibration of the said armature in the 15 said position.

2. In a signalling apparatus, an electromagnet with its pole piece, an armature oscillatably mounted with respect to the pole of the magnet, a signal element connected 20 to the armature for movement therewith, the said armature and signal element being movable in one direction into an active position when the magnet is energized and being movable in another direction into an 25 inactive position by the action of gravity, the pole piece having an extension providing a magnetic path for the lines of flux and a stop means for limiting the motion of the armature in both directions, said magnet 30 pole piece and armature including means whereby the magnetic pull of the energized magnet on the armature will move the same to one of said limiting positions and when in such position will exert a magnetic moment 35 on the armature about the axis of oscillation effective to force the armature against the stop means to prevent vibration of the same in the said limiting position, there being also a gravity moment 40 about the axis of oscillation when the armature is in its inactive limiting position to force the armature against the stop means to prevent vibration of the same in the said latter limiting position, whereby a substantially 45 vibrationless signalling apparatus is obtained.

3. In a signalling apparatus, an electromagnet with its pole piece, a bracket associated with said pole piece and providing a magnetic path for the lines of flux, an armature pivotally mounted on the bracket and adapted to move relatively to the pole of the magnet, a signal element connected to the armature for movement therewith, the bracket being also a stop means engageable with a portion of the armature to limit movement of the same in one direction and with a portion of the signal element to limit movement of the same in the opposite direction, said magnet pole piece and armature including means whereby the magnetic pull of the energized magnet will pull the armature to the first mentioned limiting position and when in the said position will exert a magnetic moment about the pivotal axis of the armature 55

axis of the armature effective to force the armature against the stop means to prevent vibration.

4. In a signalling apparatus, an electromagnet with its pole piece, a bracket magnetically connected with said pole piece and providing a magnetic path for the lines of flux, an armature pivotally mounted on the bracket and adapted to move relatively to the pole of the magnet, a signal element 70 connected to the armature for movement therewith, the bracket being also a stop means engageable with a portion of the armature to limit movement of the same in one direction and with a portion of the signal element to limit movement of the same in the opposite direction, said magnet pole piece and armature including means whereby the magnetic pull of the energized magnet will pull the armature to the first 75 mentioned limiting position and when in the said position will exert a magnetic moment about the pivotal axis of the armature effective to force the armature against the stop means to prevent vibration, and 80 when the magnet is deenergized a gravity moment will move the armature and signal element to the second mentioned limiting position and will be active to force the signal element against the stop means to prevent vibration. 85

5. In a signalling apparatus, an electromagnet with its pole piece, a bracket magnetically connected with said pole piece and providing a magnetic path for the lines of flux, a laminated armature including spaced magnetic laminæ portions and an intermediate non-magnetic lamina portion pivotally mounted on the bracket and adapted to move relatively to the pole of the magnet, a signal element 100 connected to the armature for movement therewith, the bracket being also a stop means engageable with the non-magnetic portion of the armature to limit movement of the same in one direction, said magnet pole piece and armature including means whereby the magnetic pull of the energized magnet will pull the armature to the said limiting position and when in the said position will exert a magnetic moment about 105 the pivotal axis of the armature effective to force the armature against the stop means to prevent vibration. 110

6. In a signalling apparatus, an electromagnet with its pole piece, a bracket magnetically connected with said pole piece and providing a magnetic path for the lines of flux, an armature pivotally mounted on the bracket and adapted to move relatively to the pole of the magnet, a signal element 120 connected to the armature for movement therewith, the bracket being also a stop means for limiting the movement of the armature and the signal element in opposite directions, said magnet pole piece 125

130

and armature including means whereby the magnetic pull of the energized magnet will pull the armature to one of the limiting positions in one direction and when in the said position will exert a magnetic moment about the pivotal axis of the armature effective to force the armature against the stop means to prevent vibration.

7. In a signalling apparatus, an electromagnet with its pole piece, a bracket magnetically connected with said pole piece and providing a magnetic path for the lines of flux, an armature pivotally mounted on the bracket and adapted to move relatively to the pole of the magnet, a signal element connected to the armature for movement therewith, the bracket being also a stop means for limiting the movement of the armature and the signal element in opposite directions, said magnet pole piece and armature including means whereby the magnetic pull of the energized magnet will pull the armature to one of the limiting positions in one direction and when in the said position will exert a magnetic moment about the pivotal axis of the armature effective to force the armature against the stop means to prevent vibration, the armature and the signal element being so mounted as to gravitate into its other limiting position in the opposite direction, a gravity moment being effective on the armature to force the same against the stop means in the latter limiting position to prevent vibration of the armature when in such position.

8. In a gravity reset signalling apparatus, an electromagnet with its pole piece, a bracket magnetically connected with said pole piece and providing a path for the magnetic flux, an armature pivotally mounted on said bracket, the armature being provided with an eccentric wing portion adapted to move across the pole piece face when the magnet is energized, the armature being gravitationally movable into an inactive position, the bracket being also a stop means for limiting motion of the armature into its two positions, the wing portion of the armature being arranged to engage the bracket stop means to limit the armature in its active position.

9. In a signalling apparatus, an electromagnet with its pole piece, an armature movably mounted with respect to the pole of the magnet, a signal element connected to the armature for movement therewith, the armature and the signal element being gravitationally movable into an inactive position and being movable into an active position when the magnet is energized, stop means for limiting motion of the armature in both of its positions and provisions for locking the armature in both such positions, said provisions comprising a spring pressed

plunger movably mounted in the core of the magnet.

10. In a signalling apparatus, an electromagnet with its pole piece, an armature movably mounted with respect to the pole of the magnet, a signal element connected to the armature for movement therewith, the armature and the signal element being gravitationally movable into an inactive position and being movable into an active position when the magnet is energized, stop means for limiting the motion of the armature in its gravitated position and unitary provisions for locking the armature in both of its positions, the said provisions being operative on the armature when in its inactive position to force the same against the stop means.

11. In a signalling apparatus, an electromagnet with its pole piece, an armature movably mounted with respect to the pole of the magnet, a signal element connected to the armature for movement therewith, the armature and the signal element being gravitationally movable into an inactive position and being movable into an active position when the magnet is energized and provisions for locking the armature in its active position, said provisions comprising a plunger movable in the core of the magnet and engageable with the armature for retaining the same in its active position.

12. In a signalling apparatus, an electromagnet with its pole piece, an armature movably mounted with respect to the pole of the magnet, a signal element connected to the armature for movement therewith, the armature and the signal element being gravitationally movable into an inactive position and being movable into an active position when the magnet is energized, a non-magnetic element forming part of the armature and provisions for locking the armature in its active position, said provisions comprising a plunger movable in the core of the magnet and engageable with the non-magnetic element of the armature for retaining the same in its active position while minimizing the magnetic adhesion between the parts.

13. In a signalling apparatus, an electromagnet with its pole piece, an armature movably mounted with respect to the pole of the magnet, a signal element connected to the armature for movement therewith, the armature and the signal element being gravitationally movable into an inactive position and being movable into an active position when the magnet is energized, provisions for locking the armature in its active position, said provisions comprising a plunger movable in the core of the magnet and engageable with the armature for retaining the same in its active position and means comprising a solenoid active on said

plunger for moving the same to inoperative position to permit armature movement to inactive position.

14. In a signalling apparatus, an electromagnet with its pole piece, an armature movably mounted with respect to the pole of the magnet, a signal element connected to the armature for movement therewith, the armature and the signal element being 5 gravitationally movable into an inactive position and being movable into an active position when the magnet is energized, provisions for locking the armature in both of its said positions comprising a spring 10 pressed plunger movable in the core of the magnet and having a portion normally in the path of armature movement and engageable with the armature for locking the same in its inactive position and solenoid 15 means in series with the magnet coil operative for moving the plunger out of the path of armature movement when the magnet is energized, cessation of magnet and solenoid 20 excitation causing the plunger to move 25 into its normal position to engage the armature to lock the same in its active position.

15. In a signalling apparatus, an electromagnet with its pole piece, an armature 30 movably mounted with respect to the pole of the magnet, a signal element connected to the armature for movement therewith, the armature and the signal element being 35 gravitationally movable into an inactive position and being movable into an active position when the magnet is energized, provisions for locking the armature in both 40 of its said positions comprising a spring pressed plunger movable in the core of the magnet and having a portion normally in the path of armature movement and engageable with the armature for locking the same in its inactive position, solenoid means 45 in series with the magnet coil operative for moving the plunger out of the path of armature movement when the magnet is energized, cessation of magnet and solenoid 50 excitation causing the plunger to move into its normal position to engage the armature to lock the same in its active position and means including a second solenoid operative 55 to move the plunger to inoperative position to permit armature movement to inactive position, cessation of excitation of the said second solenoid causing the plunger to again move into operative position to lock the armature in its inactive position.

16. In a signalling apparatus, an electromagnet with its pole piece, an armature 60 movably mounted with respect to the pole of the magnet, a signal element connected to the armature for movement therewith, the armature and the signal element being 65 gravitationally movable into an inactive position and being movable into an active

position when the magnet is energized, provisions for locking the said armature in position comprising a plunger movable in the magnet core and normally positioned in the path of armature movement and solenoid 70 means in series with the magnet core operative for moving the plunger out of path of armature movement when the magnet is energized, cessation of magnet and solenoid 75 excitation causing the plunger to move into its normal position to engage the armature to lock the same in its active position.

17. In a signalling apparatus, an electromagnet with its pole piece, an armature 80 movably mounted with respect to the pole of the magnet, a signal element connected to the armature for movement therewith, the armature and the signal element being 85 movable into an active position when the magnet is energized and into an inactive position when the magnet is deenergized, a stop means for limiting the motion of the armature in its inactive position and unitary 90 provisions for locking the armature in both of its positions, the said provisions being operative on the armature when in its inactive position to force the same against the stop means.

18. In a signalling apparatus, an electromagnet with its pole piece, an armature 95 movably mounted with respect to the pole of the magnet, a signal element connected to the armature for movement therewith, the armature and the signal element being 100 movable into an active position when the magnet is energized and into an inactive position when the magnet is deenergized, provisions for locking the armature in both 105 of its said positions comprising a spring pressed plunger movable in the core of the magnet and having a portion normally in the path of armature movement and engageable with the armature for locking the same in its inactive position and solenoid 110 means in series with the magnet coil operative for moving the plunger out of the path of armature movement when the magnet is energized, cessation of magnet and solenoid 115 excitation causing the plunger to move into its normal position to engage the armature to lock the same in its active position.

19. In a signalling apparatus, an electromagnet with its pole piece, an armature 120 movably mounted with respect to the pole of the magnet, a signal element connected to the armature for movement therewith, the armature and the signal element being 125 movable into an active position when the magnet is energized and into an inactive position when the magnet is deenergized, provisions for locking the armature in both of its said positions comprising a spring 130 pressed plunger movable in the core of the

- magnet and having a portion normally in the path of armature movement and engageable with the armature for locking the same in its inactive position, solenoid means in series with the magnet coil operative for moving the plunger out of the path of armature movement when the magnet is energized, cessation of magnet and solenoid excitation causing the plunger to move into its normal position to engage the armature to lock the same in its active position and means including a second solenoid operative to move the plunger to inoperative position to permit armature movement to inactive position, cessation of excitation of the said second solenoid causing the plunger to again move into inoperative position to lock the armature in its inactive position.
20. In a signalling apparatus, an electromagnet with its pole piece, an armature movably mounted with respect to the pole of the magnet, a signal element connected to the armature for movement therewith, the armature and the signal element being movable into an active position when the magnet is energized and into an inactive position when the magnet is deenergized, provisions for locking the said armature in position comprising a plunger movable in the magnet core and normally positioned in the path of armature movement and solenoid means in series with the magnet core operative for moving the plunger out of the path of armature movement when the magnet is energized, the cessation of magnet and solenoid excitation causing the plunger to move into its normal position to engage the armature to lock the same in its active position.
40. 21. In a signalling apparatus, a signal element, an armature, associated therewith a solenoid system for actuating the armature and locking the same in position comprising a magnet winding and its magnetic circuit operative on the armature to position the same, a plunger movable in the core of the magnet and operative for locking the armature in position and a solenoid winding in series with the magnetic winding operative to move the plunger to inoperative position to permit armature movement.
50. 22. In a signalling apparatus, a signal element, an armature, associated therewith a solenoid system for actuating the armature and locking the same in position comprising a magnet winding and its magnetic circuit operative on the armature to position the same, a plunger movable in the core of the magnet and operative for locking the armature in position, a solenoid winding in series with the magnetic winding operative to move the plunger to inoperative position

to permit armature movement and a second solenoid winding operative to move the plunger to inoperative position without energizing the magnet winding.

23. In a signalling apparatus, a signal element, an armature, associated therewith a solenoid system for actuating the armature and locking the same in position comprising a magnet winding with its core, a solenoid winding in series with said magnet winding and having a core alined with the magnet core; there being a nonmagnetic gap between the said cores, a spring pressed plunger movable within the alined cores and a second solenoid winding independent of the other winding concentrically mounted with respect to the first solenoid winding.

24. In a signalling apparatus, a signal element, an armature, associated therewith a solenoid system for actuating the armature and locking the same in position comprising a magnet winding with its core, a solenoid winding in series with said magnet winding and having a core alined with the magnet core; there being a nonmagnetic gap between the said cores, a spring pressed plunger movable within the alined cores, a second solenoid winding independent of the outer winding concentrically mounted with respect to the first solenoid winding, a bracket magnetically connected to one of the cores and supporting the magnet windings and a magnetic plate between the windings and connected magnetically to said bracket.

25. In a signalling apparatus, a signal element, an armature, associated therewith a solenoid system for actuating the armature and locking the same in position comprising a magnet winding with its core, a solenoid winding in series with said magnet winding and having a core alined with the magnet core; there being a nonmagnetic gap between the said cores, a spring pressed plunger movable within the alined cores, a second solenoid winding independent of the other winding concentrically mounted with respect to the first solenoid winding, a bracket magnetically connected to one of said cores and supporting the windings, the said bracket being provided with a portion spaced from the other core to provide an air gap therebetween and an armature pivotally mounted on the said bracket portion and adapted to move with respect to said core during magnet energization to substantially close the said air gap.

Signed at New York, in the county of and State of New York, this 15th day of February A. D. 1921.

CHARLES HERRMANN.
